UNITED STATES PATENT OFFICE.

LOUIS S. BURBANK, OF HOPEDALE, MASSACHUSETTS.

PUZZLE.

1,071,874.

Specification of Letters Patent.

Patented Sept. 2, 1913.

Application filed December 13, 1912. Serial No. 736,539.

To all whom it may concern:

Be it known that I, LOUIS S. BURBANK, a citizen of the United States, and a resident of Hopedale, in the county of Worcester and State of Massachusetts, have invented certain new and useful Improvements in Puzzles, of which the following is a specification.

This invention in its preferred form is embodied in a puzzle comprising two flat members or plates pivotally connected at their central portions and lying side by side, each member having a plurality of slots differing in form and arrangement from the 15 slots in the other member, and a plurality of headed buttons or slides engaged with the slots in the two members and movable progressively from the central to the outer portion of the puzzle by rotative manipulation 20 of the members to cause the intersection of the different portions of the slots, the feat to be accomplished being to move all the slides from the inner to the outer ends of the slots, this feat being rendered difficult 25 of accomplishment by peculiarities in the form of the slots, all as hereinafter described.

Of the accompanying drawings: Figure 1 represents a view of one side of the puzzle 30 embodying my invention. Fig. 2 represents a view of the opposite side of the puzzle. Fig. 3 represents a view of one of the members of the puzzle separated from the other. Fig. 4 represents a section on line 4—4 of 35 Fig. 1. Fig. 5 represents a fragmentary view showing a modification. Fig. 6 represents a side view of a modification. Fig. 7 represents a section on line 7—7 of Fig. 6.

The same reference characters indicate 40 the same parts in all the figures.

In Figs. 1 to 5, 12 and 13 represent the slotted members of the puzzle, the same being preferably made of sheet metal although any suitably stiff and relatively thin sheet 45 material may be used. A pivotal connection is provided between the central portions of said members whereby either may be rotated relatively to the other. As here shown, the pivotal connection is a stud 14 50 which may also serve as a handle, said stud passing through orifices in the central portions of the members 12 and 13 and being provided with a head 15 bearing on the outer side of the member 13. The member 55 12 is a disk provided with a plurality of sinuous slots each composed of curved portions 16 which are substantially concentric

with the pivot and connecting portions 17 which are substantially radial to the pivot, the portions 16, 17 forming a continuous 60 sinuous slot extending from a point near the center to a point near the margin of the member 12. The outer end of each slot has an enlargement 18. The member 13 is preferably cruciform and each of its arms 65 is provided with a substantially straight slot 19, the number of the straight slots being equal to the number of sinuous slots in the member 12, each member having four slots in the embodiment of the invention 70 here shown.

When the members are relatively adjusted as shown by Figs. 1 and 2, the inner ends of the slots in one member coincide with or intersect the inner ends of the slots of the 75 other member. To complete the puzzle, I provide a plurality of slides 20 each composed of two heads and an intermediate shank, the shanks of the slides being adapted to move in the slots of the members 12 80 and 13 while the heads are of greater diameter than the width of said slots. The number of slides corresponds with the number of slots in each of the members, four slides being provided in the present case. 85

When the puzzle is set for operation the slides 20 occupy the coinciding inner ends of the slots in the members 12 and 13, as shown in Figs. 1 and 2, the heads of the slides bearing on the outer surfaces of the 90 members 12 and 13 and preventing separation of said members. The feat to be accomplished is to move all the slides into the enlargements 18 of the sinuous slots. In accomplishing this feat the members 12 and 13 95 are rotatively manipulated, the sinuous form of the slots in the member 12 requiring short partial rotations of one member relatively to the other in opposite directions. If the sinuous slots were uniformly shaped 100 this feat would be comparatively easy. To render the feat difficult of accomplishment, I vary the form of the sinuous slots as indicated clearly by Fig. 3 in which it will be seen that the concentric portions 16 of the 105 sinuous slots are of different lengths so that the slides starting from the closed ends of the inner concentric portions can not simultaneously reach the inner radial portions 17. The same statement applies to each of 110 the concentric portions 16 excepting the outer ones. It is necessary therefore, to move the slides and the members 12 and 13 in different directions a large number of

times before all the slides can be brought into the outer concentric portions of the sinuous slots. I have found in practice that not less than 681 movements are required to accomplish the described feat, the form of the sinuous slots being as represented. When the slides reach the enlargements 18 the member 12 may be lifted from the member 13 and the pivot 14, the enlargements 18 being wider than the diameter of the heads of the slides, and the member 12 being movable from the pivot. If desired, however, the slots 19 in the member 13 may have enlargements 22, Fig. 5, through which the slide heads may pass, in which case it will not be necessary to separate the member 12 from the member 13.

The modified form of puzzle shown by Figs. 6 and 7 composes two flat members 120 and 130. The member 120 has a plurality of sinuous slots each composed of parallel portions 160 and connecting portions 170, one end of each sinuous slot having an enlargement 180. The member 130 has straight slots 190 extending across the parallel portions 160, the member 130 being movable relatively to the member 120 in directions parallel with the portions 160. Means are provided for maintaining the member 130 with its slots substantially at right angles with the parallel portions of the sinuous slots, and at the same time permitting the described relative movements of the members. As here shown, the member 130 is provided with ears 131 which engage and are adapted to slide on opposite ends of the member 120.

The sinuous slots differ in form from each other as indicated by Fig. 6, and the slides 20 are engaged with the inner end portions of the sinuous slots and with connecting portions of the slots 190 when the puzzle is set for operation.

Practically the same manipulation is required to solve the puzzle as with the construction first described, the movements of each member relatively to the other being rectilinear instead of rotary.

While I have shown the member 130 provided with a plurality of independent slots 190, it is obvious that these slots may be connected to form a single elongated slot. The intermediate portion or portions of such single slot between the adjacent portions of the sinuous slots will not be operative, however, since the slides will never enter said intermediate portions, so that, in effect, the member 130 will have a plurality of slots 190.

60 The construction shown by Figs. 1 to 4 is preferable on account of its compactness, it being obvious that the member 120, if provided with four sinuous slots, will neces-

sarily be much longer than the diameter of the member 12.

65

I claim:—

1. A puzzle comprising two slotted members having a central pivotal connection, one member being provided with a series of substantially straight slots radiating from the pivotal connection, and the other with a series of sinuous slots each composed of a plurality of curved portions substantially concentric with said pivotal connection, and radial portions connecting the curved portions to form a continuous sinuous slot extending from the central portion nearly to the margin of said member, and a plurality of headed slides engaged with the slots in the two members and movable progressively outward by rotative manipulation of the members to cause the intersection of different portions of the slots, the sinuous slots being differently formed.

75

2. A puzzle comprising two slotted members having a central pivotal connection, one member being provided with a series of substantially straight slots radiating from the pivotal connection and the other with a series of sinuous slots each composed of a plurality of curved portions substantially concentric with said pivotal connection, and radial portions connecting the curved portions to form a continuous sinuous slot extending from the central portion nearly to the margin of said member and a plurality of headed slides engaged with the slots in the two members and movable progressively outward by rotative manipulation of the members to cause the intersection of different portions of the slots, the sinuous slots being differently formed and provided with enlargements at their outer ends whereby the separation of the members is permitted.

85

3. A puzzle comprising two slotted members connected to permit a movement of either member relatively to the other in predetermined directions, one member being provided with a series of sinuous slots each composed of substantially parallel portions and connecting portions, while the other member is provided with substantially straight slots extending across the parallel portions of the sinuous slots, and a plurality of headed slides engaged with the slots in the two members and movable progressively therein by relative movements of the members to cause the intersection of different portions of the slots, the sinuous slots being differently formed.

90

In testimony whereof I have affixed my signature, in presence of two witnesses.
